UNITED STATES PATENT OFFICE.

CHARLES H. BOECK, OF JACKSON, MICHIGAN, ASSIGNOR TO WHITE FROST
REFRIGERATOR CO., OF JACKSON, MICHIGAN.

DESIGN FOR A LIQUID-COOLER AND BASE.

46,894.

Specification for Design.

Patented Feb. 2, 1915.

Application filed November 16, 1914. Serial No. 872,482. Term of patent 14 years.

To all whom it may concern:

Be it known that I, CHARLES H. BOECK, a citizen of the United States, residing at Jackson, in the county of Jackson and State of Michigan, have invented a new, original, and ornamental Design for a Liquid-Cooler and Base, of which the following is a specification, reference being had to the accompanying drawing, forming a part thereof.

The figure is a perspective view of a liquid cooler and base, showing my new design.

I claim:

The ornamental design for liquid cooler and base, as shown.

CHARLES H. BOECK.
